CLAIM

The ornamental design for a container for a candle, as shown and described.

DESCRIPTION

FIG. 1 is a top and side perspective view of an empty container showing a first embodiment of our design;

FIG. 2 is a bottom plan view thereof;

FIG. 3 is an elevational view thereof;

FIG. 4 is a top and side perspective view of a container including a candle showing a second embodiment of our design;

FIG. 5 is a bottom plan view thereof which is essentially identical to FIG. 2; and,

FIG. 6 is an elevational view thereof.
